UNITED STATES PATENT OFFICE.

RODOLFO GASPARIK, OF BUENOS AIRES, ARGENTINA.

MECHANICAL FILING MACHINE.

Application filed May 14, 1923, Serial No. 639,027, and in Argentina December 12, 1922.

The present invention relates to a mechanical filing machine and is a continuation in part of my copending application for Letters Patent of the United States, Serial Number 622,143, filed March 1, 1923.

An important object of the invention is to provide a machine for use with filing systems and in which any desired card or a number of cards of the same classification may be readily produced for inspection.

A further object of the invention is to so construct the machine that it can be readily determined whether or not a particular card is in its proper place.

A further object of the invention is to design the machine so that the receptacles in which the cards are carried can be placed in the machine in arbitrary sequence and without regard to the relative position of the designation of the card carried thereby in the series of indicia used.

Another object of the invention is to provide means to successively and selectively place obstructions against lateral movement of the receptacles into a position in which these obstructions cease to act as such.

Another object of the invention is to provide means constantly acting to shift each receptacle laterally, so that the receptacle in which the obstructions have been removed by placing them in the right position is shifted to a position different from the balance of the set of receptacles.

Another object of the invention is the provision of a keyboard similar to that of a typewriter so that by depressing the keys corresponding to the name or number on the card wanted, the obstructions are placed in the right position with regard to said card and permit movement of the same.

Still a further object of the invention is the provision of means by which the designation spelled out on the keyboard will appear and be visible through an opening in front of the machine.

A final object of the invention is the provision of means to restore the machine to initial position.

Further objects of the invention will appear in the following detailed description, taken in connection with the accompanying drawings forming a part of this specification, and in which:

Fig. 1 is a top plan view of the machine.
Fig. 2 is a side perspective view of the machine with the side wall removed.

Fig. 3 is a top plan view of the key levers and the cooperating plates.

Fig. 4 is a side elevation of the key levers and cooperating pivotally joined elements. 60

Fig. 5 is a section on line 5-5 of Fig. 3.

Fig. 6 is a cross-section on the line 6-6 of Fig. 1.

Fig. 7 is a fragmentary side elevation of the restoring lever. 65

Fig. 8 is an enlarged side elevation of the releasing mechanism.

Fig. 9 is a perspective view of a receptacle.

Fig. 10 is a perspective view of one of the plates actuated by the key levers. 70

In the accompanying drawings wherein similar numerals refer to similar parts throughout the same; the numeral 39 indicates the casing of the machine. The casing is mounted upon a base plate 62 and the side walls of the casing are connected to the front and rear walls by means of angle irons 58. A forward shaft 11 and a back shaft 13, parallel to shaft 11, are carried between the side walls of the casing. A plurality of bell-crank levers 10 are rotatably mounted on the forward shaft 11 and an equal number of bell-crank levers 12 are rotatably carried on back shaft 13. The bell-cranks are spaced from each other by collars 64. A plurality of rods 14 connect the lower arms of the bell-crank levers 10 with the lower arms of the bell-crank levers 12 and are pivotally fastened thereto. 75

Thin bars or wires 15 severally connect the upper arms of the bell-crank levers of one set with the upper arms of the corresponding levers of the other set. 80

Each bell-crank 10 has an arcuate tab 38 projecting down from the outer end of its upper arm; the tabs 38 are of the same length and each carries at the outer periphery all the indicia used in the system. Each tab is movable in the rear of an opening 41 in the front wall of the casing of the machine, where a row of these openings 41 is provided. 85

A third cross shaft 22 is carried between the side walls of the casing parallel to and in front of the forward shaft 11 and somewhat below the latter. A number of operating levers 21 are rotatably mounted on shaft 22 and are spaced from each other by collars 65. These operating levers form a keyboard to operate the machine and each lever has at its outer end or key 20 a designation or index used in the filing system. For exam- 100
105
110

ple, if alphabetical symbols are used, each key would be marked with a letter of the alphabet.

The backward extending arms 21' of the operating levers 21 are of a length conforming to the relative position of the designation of the particular operating lever 21 in the series of indicia used. In the preferred form, if the alphabetical system is used, the operating lever 21 which carries at its key 20 the character A would have its downwardly extending arm 21' comparatively long as shown in Fig. 2, while the backward extending arm 21' for the letter Z would be comparatively short, see Figs. 3 and 4 and the length of the arms 21' for levers 21 with letters of the alphabet between these two extremes would be proportionately shorter in length, from A to Z.

The backward extending ends 21' of the levers 21 engage plates 24 slidable in vertical direction and supported by curved longitudinal bars 23. Each plate 24 has a lower extension 24' having an opening 25, Figs. 5 and 10 into which the end of the pertaining operating lever 21 extends. These extensions or tabs 24' are in the different plates at different distances from the lateral edges of the plates as shown in Fig. 3. The bars 23 are carried by brackets 59 fastened to the side walls of the casing. The innermost plate 24 cooperates with the lever 21 carrying key A and the plate 24 close to the front wall of the casing represents letter Z, Fig. 3. A rearwardly directed lip or flange 24² is provided at the upper edge of each plate 24.

A cross rod 30 is mounted on a lever 30^a which is pivoted on the shaft 22, and said cross rod rests on shoulders 21² formed on the inner arms 21' of the levers 21. Said lever 30^a is connected by a link 31, Fig. 2, to a lever 32, rotatably carried by a bracket 56 on the base of the casing. Pivoted to the rear end of lever 32 is a latch 33, having a number of teeth 33' at its upper end. The latch 33 is normally pressed against a cross bar 18, by means of a spring 34, fastened to the lever 32, so that one of the teeth engages with a tooth 47 at the upper edge of the cross bar 18, to hold the same in a certain position. The rods 14 have downwardly extending noses 17, consecutively increasing in height as shown in Figs. 6 and 8. A spring 16 fastened to each rod tends to pull the same toward the front end of the machine, while the cross bar 18 in contact with said noses 17 prevents such a movement. The free ends of the springs 16 are fastened to an angle bar 61 supported by the side walls of the casing (Fig. 2). The cross bar 18 is guided in vertical slots 46' of brackets 46 mounted on a block 40 in the rear end of the machine (Figs. 2 and 6). Fastened to the front side of block 40 are bent flat springs

48 extending under the cross bar and tending to keep the same in its uppermost position. The front lower corners of the noses 17 are cut away to present square shoulders 17'. At the first depression of a key 20, the latch 33 and the cross bar 18 are lowered sufficiently to release that bar 14 which has the nose 17 of the smallest height, and at the upward movement of the latch 33, the bar 18 is kept in its lower position by a shoulder 75 on the nose 17, of the next rod 14, so that upon the return movement of the key and the rod 14 the second tooth from the top of the latch will engage the tooth at the upper edge of the cross bar 18. Consequently, the next bar 14 will be released when another key is depressed, etc.

Slidable extensions 10' with terminal hooks 19 are provided on the lower arms of bell-crank levers 10 under control of springs 63 which are fastened with one end to the said arms and with the other end to the extensions 10' as shown in Fig. 2. When a key is depressed the hook 19 of the rod 14 released thereby will engage the lip 24² of the frame 24 which had been simultaneously raised by depression of said operating key lever 21 and the movement of the respective bell-cranks 10 and 12 and the longitudinal movement of the connecting rod 14 is thereby stopped in a selectively predetermined position, the tab 38 then displaying a corresponding character through an opening 41. The key levers are restored to their normal position by springs 26 fastened to the extensions 21' and to a cross angle bar 60 on base plate 62 of the machine. The returning key lever draws the hook 19 down against the action of spring 63. Thus the wires 15 will be held in a predetermined 100 upward position.

A transverse plate 36 is fastened to a rock shaft 37 rotatably mounted in the side walls of the casing and carrying a handle 54 on the outside of the casing. By turning the handle 54 backwards the upper bent portion of the plate 36 strikes the noses 17 of the connecting rods 14, which are in a forward position, and moves them back to their normal position, where the shoulders will be 115 engaged by the cross bar 18. The cross bar 18, yieldingly supported by the springs 48, is returned by the springs to its upper normal position (Fig. 1) when released by the latch. The latter is swung out of engagement with the cross bar by the rearward movement of the connecting rods 14, which rock a plate 35, pivotally mounted in the rear end of the casing, whereby a downwardly extending arm 35^a of the plate 35 125 engages the latch 33. A cross rod 55 limits the movement of the hand-actuated plate 36 (Fig. 2).

The numeral 27 designates card receptacles of which there may be any number, 130

ten being shown by way of example, each with a number of slots 42 extending from their lower edges. The number of slots 42 may be equal to the number of wires 15. 5 The wires are normally positioned in the lower end portions of said slots. The receptacles 27 are preferably formed of a sheet of light but suitably rigid metal and are carried by two vertical plates 28 having 10 vertical slots to receive said receptacles. The plates 28 are carried by the upper portions of the front and rear walls of the casing (Figs. 1 and 2). The upper portion of 15 the receptacle forms a closed casing, as shown in Fig. 9, and the front wall extends downwards and enters the vertical slots of the plates 28. A hook 44 is bent out of the front wall towards the rear to hold the card in position. A marginal portion extending 20 from the lower left-hand corner Fig. 6, upward to a point about midway between the upper and lower horizontal edges of the receptacle 27 is cut away and the corner 45 of the card 29 held by the receptacle extends 25 into said cutaway portion. A spring 52 fastened to the casing is provided for each receptacle 27 to press it in direction towards the opposite wall of the casing. The movement of the receptacles toward this side of 30 the casing is prevented by a movable abutment 50. This ledge has a handle 49 and another downwardly extending abutment 53 for lifting the cards. The abutment 50, 53 is rotatably mounted in the front and rear 35 wall of the casing in holes 57, Fig. 2. A spring 67 fastened to an arm 66 of the abutment and to a pin 68 in the rear wall normally holds the abutment in the position shown in Fig. 6.

40 As has been heretofore explained, the thin bars or wires 15 carried by the respective pairs of bell-cranks 10 and 12, are moved upwards by the action of coil springs 16 pulling on the rods 14, when the cross bar 18 is lowered step-by-step by the depression 45 of the key levers. Each wire moves a predetermined distance according to the key lever actuated, as the bell-cranks 10 are stopped by the hooks 19 and the frames 24 50 raised into the path of said hooks 19 by the operation of the key levers 21. Each wire 15 moves in a particular vertical slot 42 of the several receptacles. Horizontal slots 43 are cut in the receptacles 27 and open into 55 the vertical slots 42. Each receptacle may have horizontal slots in as many positions as there are letters in the alphabet, and each horizontal slot is so arranged that it corresponds to the position of the wire lifted a 60 certain height by the depression of the key levers having the letters of the name on said card. Different combinations of horizontal slots are cut in the several receptacles 27 and only one receptacle will be moved by 65 one of the springs 52, to follow the movable abutment 50, when this combination is met by the proper arrangement of the wires 15. All the other receptacles will be held against lateral movement by one or several of the wires 15, which do not align with all the 70 horizontal slots in the other receptacles. The vertical slots 42 which do not contain horizontal slots 43 have a horizontal cut-out portion 69 at the lower end, to permit movement of the card which shall be produced. 75 The purpose of these cut-out portions 69 shall be illustrated by the following: Provided there are two cards one with the name Aroz and the other one with the name Aro. If the name Aroz is spelled out on the keyboard, the fourth wire lifted into a position corresponding to the letter Z will prevent movement of the card receptacle Aro, while at the depression of the letters A, R, O 80 the fourth wire which is not moved prevents lateral movement of the receptacle Aroz, as the fourth vertical slot in that receptacle has not a cut-out portion at its lower end. The lower corner of the card 29 near the abutment 53 projects into the cutaway portion 90 of the receptacle and is lifted by the abutment 53 after the receptacle in question has been moved sideways. Thus each card can be raised for inspection by spelling out the name carried by the card on the keyboard. 95

The operation is the following: 100

Provided a card with the name "Aroz" is to be produced. The key 20 for the letter A would be struck first and the cross bar 18 is lowered one step to release the first connecting rod 14 which is pulled forwards by the spring 16, and simultaneously the innermost frame 24 representing the letter A is raised by the operating lever into the path of the hook 19, carried by the first bell-crank 10. The hook 19 engages the upper lip 24² of the raised frame 24, and stops the movement of the rod 14 and the first pair of bell-cranks 10 and 12. The thin bar 105 or wire 15 carried by the first crank levers 10, 12 is thereby lifted a relatively short distance in its vertical slot 42 and registers with the horizontal slot 43, corresponding to the letter A. The keys for the remaining letters in the name would each be struck in turn and would move the wires 15 one after the other one in their vertical slots 42 to a predetermined distance whereupon the wires align with the horizontal slots 43 110 marked in Fig. 6 as corresponding with the letters "ROZ". The wire for letter R will move a relatively long distance, O will cause a somewhat shorter movement and the wire for the letter Z will move entirely to 115 the top of the slot 42. The wires are in the same position in the vertical slots 42 of all of the receptacles 27, but only one receptacle 120 will have all its horizontal slots 43 cut opposite the present position of the wires 24. Therefore, when the ledge 50 is swung out 125

only one receptacle is caused to follow it. The other receptacles are kept in position by the wires 15, not in alignment with horizontal slots. By turning handle 49 of the movable abutments 50 and 53, the abutment 50 is swung to the left from the position shown in Fig. 6 and permits lateral movement of the card receptacles. That receptacle in which the horizontal slots 43 and the cut-out portions 69 align with the wires will be shifted laterally by the spring 52 pressing against said receptacle. By further turning the handle 49, the ledge 53 is brought into contact with the lower edge of the projecting corner 45 of the card 29 to raise the latter and expose it to view.

As the key of each operating lever has been struck and the bell-cranks 10 have been moved in consecutive order, the tabs 38 carried by said bell-cranks 10 have been raised, so that the letters of the word align with the openings 41 in the front of the casting. The letters Aroz are thus shown in the openings 41. The card 29 can be dropped back into the receptacle, and shifted laterally into its initial position by a reverse movement of the handle 49. By turning the handle 54, the connecting rods 14 are restored and the latch 33 is swung out by means of the plate 35 to release the cross bar 18 which is pressed upwards by the springs 48 against the upper shoulder of the first connecting rod 14. The movement of the plate 36 is limited by the cross rod 55. The plate 36 is then moved back to its normal position and the upper tooth of the latch 33 engages the projection 47 of the cross bar 18. The machine is then ready for the next operation. The receptacles shown have only four slots but any number of slots may be employed.

A machine in which the receptacles can be always readily located, whether they are in arbitrary position or not, is thus provided and if the receptacle has the wrong card therein the mistake can be easily ascertained.

Means to hold the cards in the receptacles so that they cannot be removed therefrom past the position they assume when the top portion is exposed to view by the raising ledge 53 might of course be provided. It will also be understood that any system of indicia might be used with the machine and the receptacles and cards carried thereby.

With only four vertical slots in the receptacles and only 10 key levers, for instance when figures are used, 9999 combinations are possible. As the number of vertical slots can be increased to 10, 20 or more, the number of combinations is practically unlimited, especially when the keyboard has 26 keys, if alphabetical symbols are used.

It is to be understood that the form of my invention shown and described is to be taken as a preferred example of the same,

and changes in the size, shape and arrangement of parts may be resorted to without departing from the spirit of the invention or the scope of the subjoined claims.

I claim:—

1. A mechanical filing and classifying machine comprising a plurality of receptacles arranged for lateral movement, means for selectively placing obstructions against the lateral movement of said receptacles into predetermined positions whereby certain of the receptacles will be released, and means constantly acting upon each receptacle to move that receptacle, from which the obstructions are released, to a position different from the balance of the set of receptacles.

2. A mechanical filing and classifying machine comprising a plurality of key devices, a plurality of receptacles having keyways therein in which said key devices respectively are adapted to be moved, said keyways having slot formations branching therefrom, means to move said key devices predetermined distances in their respective keyways so as to coat with the slot formations in certain receptacles, and means to move said receptacles at an angle to the path of movement of said key devices.

3. A mechanical filing and classifying machine comprising a plurality of key devices, a plurality of receptacles having keyways therein in which said key devices respectively are adapted to be moved, said keyways having slot formations branching therefrom, means to move said key devices predetermined and variable distances in their respective keyways so as to coat with the slot formations in certain receptacles, and means to move said receptacles at an angle to the path of movement of said key devices.

4. A mechanical filing and classifying machine comprising a plurality of key devices, a plurality of card receptacles mounted above said key devices and having keyways therein in which said key devices are adapted to be moved, means to move said key devices predetermined distances in said keyways, said receptacles having keyways cut at right angles to said first-named keyways according to the designation of the card carried thereby, and means to move a desired receptacle laterally when said key devices are properly aligned in said first named keyways with said second-named keyways.

5. A mechanical filing and classifying machine comprising a plurality of pivotally jointed groups of elements, a plurality of thin bars one carried by each of said groups of elements, selectively operated means to move said groups of elements consecutively, to carry said thin bars upwardly predetermined distances, card receptacles mounted

above said thin bars, and provided with a series of slots and means to move the desired receptacle when the thin bars are moved to align with the slots in said card receptacle.

6. A mechanical filing and classifying machine comprising a plurality of pivotally jointed groups of elements, a plurality of thin bars, one carried by each of said groups of elements, selectively operated means to move said groups of elements successively to carry said thin bars predetermined distances, card receptacles mounted above said thin bars and provided with a series of vertical slots, a series of horizontal slots opening into said vertical slots and horizontal cut-out portions at the lower ends of those vertical slots, from which horizontal slots do not extend, and means to move the desired receptacle, when the thin bars are moved to align with the horizontal slots in said card receptacle or remain in position to align with the cut-out portions at the lower ends of the vertical slots of said card receptacle.

7. A mechanical filing and classifying machine comprising a plurality of pivotally jointed groups of elements, wires connecting the upper ends of said groups of elements, means to move said groups of elements, means to stop the movement of said groups of elements, operating key levers controlling the first-named means and actuating the second-named means to consecutively move said wires upwardly certain distances according to the designation of the key lever operated, means to hold the said groups in the predetermined positions, card receptacles mounted above said wires and having a series of right-angled slots cut therein according to the designation of the card carried by each, and means to move the desired receptacle laterally when the wires are moved to align with the slots in the card receptacle.

8. A mechanical filing and classifying machine comprising a plurality of bell-cranks, a second set of bell-cranks opposite said first set of bell-cranks, means to connect opposite bell-cranks of said sets to move in pairs, wires connecting the upper ends of the bell-cranks in each of said pairs, receptacles above and at right angles to said wires and having vertical slots to fit over said wires and combinations of horizontal slots opening into said vertical slots, means to move said pairs of bell-cranks consecutively to move said wires carried thereby certain distances upwardly, to align with a desired combination of horizontal slots, and means to move the desired receptacle laterally.

9. A mechanical filing and classifying machine comprising a plurality of pivoted groups of frames, wires carried at the upper end of said groups of frames, receptacles above said wires and having slots therein to receive said wires and combinations of slots at an angle to said first-named slots, means to move said groups of frames and the wires carried thereby consecutively predetermined and certain distances upwardly to align with a desired combination of said second-named slots, means to move the desired receptacle laterally, cards in said receptacles, and means to raise the card from said laterally moved receptacle.

10. A mechanical filing and classifying machine comprising a plurality of pivoted groups of frames, wires carried at the upper end of said groups of frames, receptacles above said wires and having slots therein to receive said wires and combinations of slots at an angle to said first-named slots, latches to lock said groups of frames in normal position, spring means to move each of said frames to carry said wires upwardly, means to release said latches to permit said spring means to act, means to limit the movement of said frames and wires and means to move the desired receptacle laterally when the proper wires meet the combination of second-named slots therein, cards in said receptacles, and means to raise the card from said laterally moved receptacle and means to return said frames to normal position.

11. A mechanical filing and classifying machine comprising a plurality of pairs of pivotally mounted elements, wires connecting the upper ends of the elements of said pairs, rods connecting the lower ends of the elements of said pairs, spring means to move each of said rods, each of said rods having a nose of different height, a cross bar in contact with said noses and locking the frames in position, a toothed latch engaging said bar, key levers actuating said latch at each operation, to lower said cross bar step-by-step and release said rods consecutively, means to limit the movement of said elements and wires, according to the key lever depressed, receptacles above said wires and having slots at an angle to said first-named slots, means to move the desired receptacle laterally, when the proper wires meet the combination of the second-named slots, cards in said receptacles and means to raise the card from said laterally moved receptacle and means to return the rods, the cross bar and the latch to normal position.

In witness whereof I affix my signature.

RODOLFO GASPAKIK.
